UNITED STATES PATENT OFFICE.

EFREM MIHALOVICH, OF CHISHOLM, MINNESOTA.

FIRE-CONTROLLING APPARATUS.

Application filed September 1, 1920. Serial No. 407,387.

To all whom it may concern:

Be it known that I, EFREM MIHALOVICH, a citizen of Russia, residing at Chisholm, county of St. Louis and State of Minnesota, have invented certain new and useful Improvements in Fire-Controlling Apparatus, of which the following is a specification.

This invention has as its object the provision of means whereby the location of a fire within a compartmented building may be readily ascertained, and audible and visible signals given calling attention to the occurrence in an effective manner.

A further object is to provide means for opening a spray head in the compartment in which the fire occurs so as to present a spray of water adapted to quench the fire and thereby prevent damage from being done.

20 These and other like objects are attained by the novel construction and combination of parts hereinafter described, and shown in the accompanying drawings, forming a material part of this disclosure, and in which—

25 Figure 1 is a sectional plan view showing a conventional type of building, having a plurality of compartments and indicating the application of the apparatus.

Figure 2 is a side elevational view showing a visible signal means and the operating device connected therewith.

Figure 3 is a side elevational view of one of the audible signal devices.

Figure 4 is a vertical sectional view taken 35 on line 4—4 of Figure 5, of the spray dispensing device.

Figure 5 is a similar vertical sectional view taken on line 5—5 of Figure 4, showing the parts in another plane.

40 Figure 6 is a fragmentary side elevational view showing an auxiliary type of audible signal.

Figure 7 is a top plan view of the parts shown in Figure 3.

45 Figure 8 is a top plan view of the auxiliary audible signal means, and

Figure 9 is a longitudinal sectional view taken on line 9—9 of Figure 8.

Referring to the drawings in detail, the 50 numeral 10 indicates the front wall of a conventional type of building, containing windows 11, and having a plurality of interior partitions 12, forming compartments or rooms 13.

55 Extending inward from the rear wall 14 of the building are eyes 15 the same being

positioned near the ceiling of the room and to which are attached cords 16 which passes through appropriate openings formed in the partitions 12 and outer wall 13 into casings 18, where they are connected with levers 19, pivotally mounted in brackets 20, these levers being normally impelled forward, due to the effect of flat springs 21 in the manner best indicated in Figure 2.

60 Mounted in the levers 19 are flag staffs 23, carrying flags 24, adapted to be projected outwardly through the front of the casing, upon the rope or cord 16 becoming severed, as by a fire in the rooms through which the 65 cord passes, thus calling the attention of passers by to the existence of a fire within the building, and constituting a visible signal which can be seen from a considerable distance from the exterior of the building 70 in any direction.

75 Arranged transversely and centrally in each of the several compartments or rooms 13 are other cords 25, one end being secured to tension springs 26, set in the upper portion of the room, while the opposite ends of the cords 25 engage within casings 26, secured near the ceiling upon the opposite side of the room.

80 The inner ends of the cord 25 are directly engaged with levers 28, pivoted upon pins 29, mounted in brackets 30, the levers 28 being held normally upward against the pull of the cords 25 by springs 31, while the upper ends of the levers 28 are bevelled, as at 85 32, and adapted to make contact with bevelled projections 33 extending downward through slots 34 formed in the casings 35, arranged contiguous to the casings 26.

85 The bevelled lugs 33 form one element of 90 a bell-crank lever, the other element 36 being pivoted near its outer end to an arm 37, formed with a bar 38, held in the casing 35, which is provided with a cover 39, secured by the hinges 40 near the top of the casing 100 95 in such manner that the same may be moved therefrom.

Engaged by a pivot 41 is a link 42, pivoted by the pins 43 to a bracket 44, arranged in the bottom of the casing 35, the bracket 105 having a pair of upstanding lugs 46 and 47 respectively. Through the latter lug extends a plunger 48 having a sharpened conical point 49, and fixed upon the plunger is a collar 50, normally pressed forward, due to 110 the spring 51, abutting between the collar and lug 46, while extending from the

plunger 47 is the bar 38, the same being provided with an operating handle 52, so as to present means whereby the lever 36 and link 42 may be brought into alignment as indicated in Figure 3.

The joint pin 41, between the lever 36 and link 42, is raised whenever the projection 33 is raised, which occurs by contact of the bevelled surface 32 of the lever 28, thereby permitting the spring 51 to force the point 49 sharply forward and make contact with the head of a cartridge 54, held in a keeper 55, formed with the bracket 44, the cartridge being maintained in position by the pin or bolt 56, the cartridge used being preferably a blank, which upon being detonated produces a loud sound calling attention to the conflagration existing within the compartment.

20 A projection 58 is formed on the lower end of the lever 28, and when the spring 31 is permitted to operate, it forces the projection sharply downward making contact with a plunger 60, which upon being depressed against the spring 31, moves the plate 62 against contacts 63 and 64, the former passing into a casing 65, to the binding post 66, while another binding post 67 conveys current derived from any external 30 source of low voltage electrical energy through the wire 68, to one of the terminals 69, of an ordinary bell armature 70, thereby actuating a hammer 71 so as to make contact with the bell 72 causing the same to 35 ring so long as the circuit is closed by the depressed plunger 60.

The contact plate 62, when in a lowered position, also comes into engagement with the contacts 74 and 75, connected with the 40 lead wires 76 and 77 so that the current entering through the connection 78 is distributed through the connections, thereby closing an auxiliary circuit directly connected with the fire compartment alarm system.

45 From the foregoing it will be seen that a visible alarm as indicated in Figure 2, is operated upon the inception of a fire sufficient to consume the cords 16 in any part of the building, and coincidently with disruption of the cords 25, in any of the several rooms, causes the explosion of a cartridge, torpedo, or the like, creating a sound adapted to attract attention which is maintained by the continuous ringing of the bell 55 72 attracting the attention of the passers by, while the fire department may be called by having the wires 76 and 77 properly connected.

The cords 25, entering the casings 26, are 60 also engaged with levers 80 after passing over the pulleys 81, these levers being mounted upon pivots 82 and carrying at their outer ends pins 83 by which are connected links 84 adjustably engaged at 85, 65 with arms 86, pivotally engaged at 87 with-

in the casing 26, the extreme outer end of the arms 86, have secured upon them open top hollow containers 88 adapted to receive liquids and which have at their lower end valves 89, the projecting stems 90 terminating in blocks 91, which may, upon the arms 86 becoming lowered, make contact with fixed projections 92, secured within the casing.

Carried by the opposite ends of the levers 75 80 are blocks 95 supporting springs 96 adapted to actuate valves 105 controlling the passage within the pipes 97, these pipes being fed by inlets 98 from any convenient source of supply, as a tank upon the roof, 80 or service pipe of the building.

The outer end of the pipes 97 terminate in a downturned spray head 100 of the usual type, adapted to dispense water from the pipe over a considerable radius when 85 the valve is in an open position.

A feeder pipe 101 is connected with the main pipe 97 at one end, has its lower, angular end 32 so disposed as to admit a small quantity of water into the container 88, 90 causing it to tilt the arm 86 upon its fulcrum and normally raise the lever 80, momentarily until the valve 89 has become opened releasing the contents, whereupon the same effects are repeated.

From the foregoing it will be seen that an effective device for dispensing water in the form of spray into any of the several compartments has been disclosed, operative upon the burning of the transversely disposed cords 25 due to the effect of the fire within the compartment, and providing an effective and automatically operated means for controlling and quenching a fire in its incipient stage.

Having thus described my invention what I claim as new and desire to secure by Letters Patent, is—

1. In a fire controlling apparatus, the combination with a cord engaged at one end within the room of a building and a casing supported upon the outer walls of said building into which said cord enters, of a lever mounted in said casing at its lower end, connections between said lever and said cord, a spring adapted to force said lever outwardly, and a flag carried by said lever adapted to be normally disposed within said casing, said flag being liberated upon the disruption of said cord.

2. In a fire controlling apparatus, the combination with a hollow casing secured upon the outer wall of a building, a lever pivoted in the lower end of said hollow casing, means adapted to force the free end of said lever outwardly, a flag carried by said lever normally disposed in said casing and extended outwardly upon the operation of said spring, and a cord attached to said lever at one end for holding said lever in 130

concealed position, and to the opposite side of a compartment within said building at its other end, said cord being subject to disruption by heat from a conflagration for causing the flag to be displayed.

3. In a fire controlling apparatus, the combination with a casing arranged upon one side of a room, a cord entering said casing, means for attaching said cord at the 10 opposite side of said room, a lever pivotally mounted in said casing, a spring combined with said lever whereby said cord is held normally in a taut condition, a signalling means and means for releasing said signalling 15 means upon the movement of said lever, said lever being freed by rupture of said cord.

4. In a fire controlling apparatus, the combination with a casing attached to one side of a room, a cord entering said casing, 20 the opposite end of said cord being resiliently attached to the opposite wall of the room, a release lever pivoted in said casing to which said cord is attached, means for tensioning said cord and normally moving 25 said lever outwardly, a signalling means, a lever whereby said signalling means is normally held in a retracted position, and means for releasing said lever when said cord is disrupted. 30

In testimony whereof I have affixed my signature.

EFREM MIHALOVICH.
